Seth Wheeler.

UNITED STATES PATENT OFFICE.

SETH WHEELER, OF ALBANY, NEW YORK.

COPYING-MACHINE.

SPECIFICATION forming part of Letters Patent No. 314,091, dated March 17, 1885.

Application filed December 31, 1883. (No model.)

To all whom it may concern:

Be it known that I, SETH WHEELER, of the city of Albany, in the county of Albany and State of New York, have invented certain new and useful Improvements in Copying-Machines; and I do hereby declare that the following is a full, clear, and exact description thereof, reference being had to the drawings accompanying and forming part of this specification.

My improvements relate to a machine by means of which impressions may be obtained on a continuous web or roll of paper, from which web or roll the portions receiving the impressions are subsequently severed, or such portions may be severed immediately after the impressions are made. By reason of my improvements perfect impressions may be taken by hand-power to the extent of from one hundred to two hundred per minute.

In the drawings, Figure 1 is a side elevation of a machine in which are embodied my improvements, the impressions being received continuously on the surface of the paper as it is fed along from off its roll and before it is rewound on another roll. Fig. 2 is a front elevation thereof.

A is the base-plate of the machine. B B are two standards, one at each end of the said base-plate A. C is a receiving and impression roll journaled in the said standards.

D is a roll which is journaled in slotted projections E E on the standards for holding the roll or web of paper F which is to receive the impression. The openings E E of the standards serve to permit the journals of the roll D to rise therein—that is, recede from the center of the receiving and impression roll as the web is wound from off roll D onto roll C, and to have the surface of the paper constantly in contact with the periphery of said receiving and impression roll.

G is an absorbent roll, upon the periphery of which the original matter from which the impression is to be taken is transferred. In order to permit the journals H H of this absorbent roll to rise so as to just keep the roll in contact with the surface of the paper as it

is drawn from off the roll D onto the receiving-roll C, such journals are placed in slotted 50 projections I I on the standards B B.

The receiving and impression roll C has attached to one end of its shaft J a crank-handle, K, by means of which motion can be given to such roll, and the paper F be thereby drawn 55 from off the roll D and into contact with the periphery of the absorbent roll G, and after receiving impressions be wound continuously upon said roll C.

The base-plate is hinged to a table or stand 60 at L, by means of which the machine can be thrown back in the direction of the dotted line shown on Fig. 1, so as to enable the paper wound upon the roll C to be withdrawn therefrom, as may be required.

At the front part of the base-plate A is a knife-bar, M, attached by means of two screws, N N, so as to leave a space between the inner surface of the knife-bar and the front edge of the base-plate, in order that the end of the 70 paper can be withdrawn through such space from the roll C, the knife-bar M severing the paper into the required size of sheets when pressed firmly against the lower edge.

The operation of the machine is as follows: 75 The paper F passes from off the roll D onto the receiving and impression roll C, the absorbent roll containing the original matter required to be impressed thereon moving in frictional contact with roll C, and with each revolution 80 makes an impression on such surface of the paper. As fast as it is made the paper F is wound onto the roll C, to be subsequently withdrawn therefrom and cut off by means of the knife-bar M.

The absorbent roll G may, instead of having a periphery of gelatine for the original matter, as in the hektograph apparatus, contain a stencil or other suitable surface of original matter.

I claim—

1. The combination of a roll containing a web of paper with an impression and storing roll on which said paper is run and stored after it has been impressed, and an absorbent 95 roll in contact with the surface of such paper,

upon the periphery of which is transferred the surface of original matter to be impressed on the surface of the paper.

2. The combination of a roll containing a web of paper, an impression-roll on which said paper is run, an absorbent roll in contact with the surface of such paper, upon the periphery of which is transferred the surface of original matter to be impressed on the surface of the

paper, and a knife-bar for severing the paper into portions, such elements being arranged upon a base-plate which is hinged to a stand or table, substantially as described.

SETH WHEELER.
